(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image in the sequence showing our new design;

FIG. 2 is a second image thereof;

FIG. 3 is a third image thereof;

FIG. 4 is a fourth image thereof;

FIG. 5 is a fifth image thereof; and
FIG. 6 is a sixth image thereof;

FIG. 7 is a front view of a second embodiment of a display screen or portion thereof with animated graphical user interface showing a first image in the sequence showing our new design;

FIG. 8 is a second image thereof;

FIG. 9 is a third image thereof; and

FIG. 10 is a fourth image thereof;

FIG. 11 is a front view of a third embodiment of a display screen or portion thereof with animated graphical user interface showing a first image in the sequence showing our new design;

FIG. 12 is a second image thereof;

FIG. 13 is a third image thereof; and

FIG. 14 is a fourth image thereof;

FIG. 15 is a front view of a fourth embodiment of a display screen or portion thereof with animated graphical user interface showing a first image in the sequence showing our new design;

FIG. 16 is a second image thereof;

FIG. 17 is a third image thereof; and

FIG. 18 is a fourth image thereof;

FIG. 19 is a front view of a fifth embodiment of a display screen or portion thereof with animated graphical user interface showing a first image in the sequence showing our new design;

FIG. 20 is a second image thereof;

FIG. 21 is a third image thereof; and

FIG. 22 is a fourth image thereof;

FIG. 23 is a front view of a sixth embodiment of a display screen or portion thereof with animated graphical user interface showing a first image in the sequence showing our new design;

FIG. 24 is a second image thereof;

FIG. 25 is a third image thereof; and

FIG. 26 is a fourth image thereof;

FIG. 27 is a front view of a seventh embodiment of a display screen or portion thereof with animated graphical user interface showing a first image in the sequence showing our new design;

FIG. 28 is a second image thereof;

FIG. 29 is a third image thereof; and,

FIG. 30 is a fourth image thereof.

(Continued)

The outermost broken lines in the Figures illustrate a display screen or portion thereof and the remainder of the broken lines illustrate portions of the animated graphical user interface. None of the broken lines form part of the claimed design.

The appearance of the animated images transitions sequentially between the images shown in FIGS. 1-6, FIGS. 7-10, FIGS. 11-14, FIGS. 15-18, FIGS. 19-22, FIGS. 23-26, FIGS. 27-30. The process or period in which one image transitions to another forms no part of the claimed design.
